CLAIM

The ornamental design for a combination barbecue grill, cook top, and oven, as shown and described.

DESCRIPTION

FIG. 1 is a perspective view of the combination barbecue grill, cook top, and oven of my new design.

FIG. 2. Is a front elevational view thereof.

FIG. 3 is a back elevational view thereof.

FIG. 4 is a right side elevational view thereof.

FIG. 5 is a left side elevational view thereof.

FIG. 6 is a bottom plan view thereof; and,

FIG. 7 is a top plan view thereof.

The broken line figures in FIG. 1, depicting propane tanks, are environmental elements and form no part of my new design.

1 Claim, 5 Drawing Sheets
